(57) **CLAIM**

The ornamental design for a hand cart, as shown and described.

DESCRIPTION

FIG. 1 is a frontal perspective view of a hand cart according to my design;

FIG. 2 is a rear perspective view thereof;

FIG. 3 is a side view thereof, the opposite side being a mirror image thereof;

FIG. 4 is a front view thereof;

FIG. 5 is a rear view thereof;

FIG. 6 is a front perspective view thereof with a shelf in an open position;

FIG. 7 is a side view thereof with the shelf in an open position, the opposite side being a mirror image thereof;

FIG. 8 is a top view thereof; and,

FIG. 9 is a bottom view thereof.

The broken line in the reproductions depict portions of the hand cart that form no part of the claimed design.
